METHOD OF FORMING A HEAT EXCHANGE DEVICE

John Karmazin, Huntington, Ind., assignor to
General Motors Corporation, Dayton, Ohio, a
corporation of Delaware

Application May 7, 1935, Serial No. 20,206

3 Claims. (Cl. 29—157.3)

This invention relates to refrigerating apparatus and more particularly to a novel heat exchange device for use in refrigerating apparatus and for other purposes.

Heretofore, in constructing heat exchangers of the type comprising a plurality of parallel tubes usually having fins thereon, the necessity of connecting together the ends of the parallel tubes in some manner has presented a problem. For example, if it is desired to connect the ends of a plurality of tubes into a single header for placing the tubes in parallel circuit relation, the header constructions heretofore employed have necessitated the use of individual dies for each size of heat exchanger which is constructed. In supplying the needs of the trade, it is necessary that a large range of sizes be manufactured, due to the many varied individual requirements imposed by the various applications for heat exchange structures. In meeting these requirements, particularly for heat exchangers having their tubes connected in parallel circuit relation, the cost of the different dies and other machine tools which must be constructed individually for each different size of heat exchanger has contributed materially to the high cost of such devices particularly where the number produced in a given size is rather small.

It is an object of the present invention to provide a heat exchange structure by which greater flexibility in manufacturing the devices in various sizes is obtained without prohibitive cost for a small production of a single size of heat exchangers.

More particularly, it is an object to provide a heat exchanger and header construction therefor, by which the same set of manufacturing tools and machinery may be utilized for producing heat exchangers having headers of various lengths without the necessity of individual dies and tools for each individual length.

It is a further object of the invention to provide a novel method of producing heat exchangers and headers therefor from sheet metal at low cost.

Further objects and advantages of the present invention will be apparent from the following description, reference being had to the accompanying drawing, wherein a preferred form of the present invention is clearly shown.

In the drawing:

Fig. 1 is a view in elevation of heat exchanger constructed according to the present invention;

Fig. 2 is a cross section on line 2—2 of Fig. 1;

Fig. 3 is a cross section on line 3—3 of Fig. 2;

Fig. 4 is a perspective view of a portion of the header construction at an intermediate state of manufacture;

Fig. 5 is a perspective view of the second portion of the header construction at an intermediate stage of manufacture;

Fig. 6 is a perspective view of a portion of another header construction shown in an intermediate state of manufacture; and

Fig. 7 is a perspective view of another portion of a header construction shown in an intermediate stage of manufacture.

Referring now to Fig. 1, the heat exchange device comprises a heat exchange core 10 which is formed of a plurality of parallel tubes 12 and 15 transverse fins 14. The heat exchange core may be formed in any suitable manner, the core illustrated being formed from fins having integral tapered tubular projections formed therein and telescoped with similar projections of adjacent fins to provide the continuous tubes 12. Such a core construction is illustrated in more detail in the patent to Karmazin 1,997,563 issued April 9, 1935. At either end of the core 10, headers 16 and 18 are provided to connect the tubes 12 in parallel circuit relation. Suitable inlet and outlet connections 20 and 22 are provided in the headers 16 and 18 respectively.

Each of the headers 16 and 18 are formed somewhat similarly in order to admit of a process 30 being utilized whereby different lengths of header for different heat exchangers do not necessitate the use of individual tooling for each length. Thus, each header is formed from a pair of channel-like members which may be cut from a 35 long strip of channel-like material in any length desired. The pair of channel-like members are telescoped together in order to provide a closed header having openings for engagement with the tubes of the heat exchanger core. The header 16, 40 for example, may be formed from a pair of lengths of channel-like strips 24 and 26 which are telescoped together as illustrated in Fig. 2.

The channel-like strip may be formed in any of a number of ways, for example, as by extrusion, 45 or by rolling or stamping from a flat strip. Either before or after the strip is given the channel-like form, suitable tubular projections 28 are formed therein at intervals corresponding to the spacing of the tubes 12. The tubular projections 28 form openings to the header 16 and in the construction illustrated are tapered to telescope into the corresponding tubular projections formed in the top fins 14 of the core. The channel-like strip from which the member 24 is cut 50

55

has a suitable opening 30 formed therein by which the inlet connection 20 is secured to the header 16. The opening 30 is preferably formed after the member 24 is cut from the strip of material of channel-like form.

The header 18 is formed by a similar process to provide a pair of channel-like members 32 and 34 corresponding respectively to the members 24 and 26. In the construction illustrated, the 10 channel-like member 34 is provided with a plurality of tubular projections 36 on the upper surface thereof which are given a reverse taper to receive the tapered tubular projections of the lower-most fin 14. The cross sectional shape of the 15 channel-like members 24, 26, 32 and 34, in the form of the invention illustrated, is approximately that of a partial cylinder. That portion of the strip 26 and strip 28 between the openings or projections 28 and 36 respectively may be either a 20 continuation of the cylindrical arc as shown in Fig. 5 or may be flat as shown in Fig. 7. When the protuberances 28 and 36 are formed after the strip is given its channel-like form, it is convenient to use the construction illustrated in Fig. 5. 25 When the protuberances 28 and 36 are formed from the flat strip, it is more convenient to utilize the form illustrated in Fig. 7. It will be understood, of course, that various other cross sectional forms may be utilized so long as the outline of the assembled channel-like members of the header provides a generally tubular structure.

After the lengths of channel-like strip have been cut from a longer piece of the same, the members 24 and 26 are telescoped together and 30 the members 32 and 34 are telescoped together as illustrated in Fig. 2. Suitable end closures 38, preferably of stamped sheet metal, are next applied to the ends of the headers 16 and 18 and the inlet and outlet connections 20 and 22 are 35 inserted in the opening 30 and a corresponding opening formed in the channel-like member 32. The headers 16 and 18 are then assembled to the core 10 and the entire structure bonded together by a suitable sealing medium. For example, the 40 heat exchanger may be sealed by copper welding in a furnace having a reducing atmosphere, or the structure may be sealed by a solder dip. While it is most convenient to seal the entire heat exchanger including the core 10 and the headers 16 and 18 at one operation, it may be 45 desirable in some cases to seal the headers 16 and 18 and the core 10 individually before assembling them together. Likewise, while the inlet and outlet connections have been illustrated as connecting at an intermediate point along the length of the header, it may be desirable in some instances 50

to connect the inlet and outlet connections at one end of the header, in which case the closure 38 at that end is omitted and the inlet or outlet connection substituted therefor.

While the form of embodiment of the invention as herein disclosed constitutes a preferred form, it is to be understood that other forms might be adopted, all coming within the scope of the claims which follow.

What is claimed is as follows:

1. The method of forming a heat exchange device which comprises the steps of forming a header by forming a pair of channel-like strips, each strip having a substantially circular segmental cross-section and an open longitudinal side and one strip having a plurality of tube engaging openings with integral tubular flanges along one wall thereof, longitudinally telescoping said pair of short lengths of strip together with the circular portions overlapping throughout approximately half their circumference, placing end cups over the ends of the telescopes, assembling a plurality of tubes into engagement with said openings and bonding the tube and header structure together with a sealing medium.

2. The method of forming heat exchange devices which comprises the steps of forming headers by forming a pair of channel-like strips, each strip having a substantially circular segmental cross-section and an open longitudinal side and one strip having a plurality of tube engaging openings along one wall thereof, telescoping said strips together with the circular portions overlapping throughout approximately half their circumference, forming fin and tube heat exchange cores, assembling the tube ends of said cores into engagement with said openings, placing end cups over the ends of the telescopes, and bonding each entire heat exchanger together by a single fused metallic sealing operation.

3. The method of forming a heat exchange device which comprises the steps of forming a header by forming a pair of channel-like strips, each strip having a substantially circular segmental cross-section and an open longitudinal side and one strip having a plurality of tube engaging openings along one wall thereof, longitudinally telescoping said pair of strips together with the circular portions overlapping throughout approximately half their circumference, forming a fin and tube heat exchanger core, assembling the tube ends of said core into engagement with said openings and bonding the entire exchanger together by a single fused metallic sealing operation.
